UNITED STATES PATENT OFFICE.

STALEY D. POOLE, OF MOLINE, ILLINOIS, ASSIGNOR TO DEERE & COMPANY, OF MOLINE, ILLINOIS, A CORPORATION OF ILLINOIS.

FASTENING FOR HARROW-TEETH.

SPECIFICATION forming part of Letters Patent No. 691,660, dated January 21, 1902.

Application filed July 25, 1901. Serial No. 69,662. (No model.)

To all whom it may concern:

Be it known that I, STALEY D. POOLE, a citizen of the United States, residing at Moline, in the county of Rock Island and State of Illinois, have invented certain new and useful Improvements in Fastenings for Harrow-Teeth; and I do hereby declare the following to be a full, clear, and exact description of the invention, such as will enable others skilled in the art to which it appertains to make and use the same.

This invention relates to means for fastening or securing harrow-teeth in place upon the bars or supports therefor; and it consists, substantially, in the improvements hereinafter more particularly described, and pointed out in the claims.

The object of the present invention is to provide a clip or fastening device of the character referred to which is simple in construction and thoroughly effective in use and one also which is capable of being quickly and readily applied without much labor and without special tools for the purpose.

A further object is to provide a clip or device of a construction whereby the fastening of the harrow-tooth is rendered as strong and durable by the employment of ordinary cast-iron in the manufacture thereof as former constructions in which malleable iron is employed.

A still further object of the invention is to provide a clip or fastening device for the purpose named which is capable of being rapidly produced in unlimited quantities with fewer defects than hitherto and also with a much greater uniformity of the sizes thereof throughout.

The above and additional objects I attain by means substantially such as are illustrated in the accompanying drawings, wherein—

Figure 1 is a view in perspective of a harrow-bar section, showing my improved device or fastening for securing the harrow-tooth in proper position upon the bar. Fig. 2 is a central longitudinal sectional view of Fig. 1; and Fig. 3 is a transverse sectional view thereof, taken centrally of the bolt by which the clip or fastening device is fastened or secured to the bar. Fig. 4 is a top plan view with the harrow-tooth in section, and Fig. 5 is a bot-

tom plan view. Fig. 6 is an end elevation looking toward the left. Fig. 7 is a perspective view of the clip detached and taken from the inner face thereof.

55

Specific reference being had to the accompanying drawings, A represents a harrow-bar section constructed of metal and of substantially semitubular form, the longitudinal straight edges *a a* thereof being in the same vertical plane, as shown. In the vertical or rounded side *b* of said bar an opening *c* is formed for the passage of a pin or bolt *d*, which secures the clip or fastening device B to the bar, the said bolt being provided with a nut *e*, which is screwed up tightly against the bar, as shown. My improved clip or fastening device B is substantially hook-shaped in top view or horizontal section, and the neck thereof is constituted of a vertical flat portion *f*, from the inner face of which project at substantially right angles two ribs or flanges *g g*, which are separated by a space *h* for the purpose of lightness, and which ribs or flanges are received between the upper and lower sides of the supporting-bar in a manner to prevent turning of the clip or fastening device in a vertical direction when in position to secure the harrow-tooth C in place upon the said supporting-bar. At about the point of joinder or intersection of the hooked portion of the clip with the neck thereof the said clip or fastening device is formed with a bolt hole or opening *i*, corresponding with opening *c* in bar A, and the outer surface of the said hooked portion is hollowed out or recessed at *k*, both to lessen the weight of the clip and to provide a flat bearing for the head *l* of the bolt, as well as a pocket or receptacle for receiving such head in a manner to protect and partially conceal the same. The upper and lower webs or flanges *nn* thus formed on the outer surface of the clip also serve as abutments for the said bolt-head, by which the bolt is prevented from turning, and thus is increased strength also imparted to the structure, besides bringing the several parts or elements of the clip or fastening device into snug and compact relationship. The said webs or flanges *nn* are also strengtheners for the clip or fastening device, as is obvious.

100

vice is also formed on its upper and lower surfaces with a longitudinal rib or flange *o*, which for the whole or part of their length abut against the edges of adjacent portions of the longitudinal straight edges of the supporting-bar *A*, and thus is my improved clip or fastening device also prevented from turning inwardly or axially in a horizontal plane with respect to the major axis of the harrow-tooth.

10 Said ribs or flanges also serve as an abutment or resistance in the tightening of the parts in place by means of the nut on the bolt. The said clip is also ribbed, as shown at *p*, for the purpose of increasing the strength of the clip 15 at points thereof subject to the greatest amount of strain in use. On its inner or engaging face the hooked portion of the clip or fastening device is formed with a notch or recess *s*, the sides of which intersect or join each 20 other in substantially a single right angle, as shown, and said sides unite with adjacent portions of the straight edges *a a* of the supporting-bar in forming an opening in which the tooth *C* fits, one corner or angle of said 25 tooth having a double bearing on said bar edges *a a*, and two of the sides of the tooth being firmly clamped or embraced by the two sides of said notch or recess. Of course with 30 harrow-teeth of other shapes in cross-section the form of the notch or recess in the clip will be made to correspond therewith.

From the foregoing description and accompanying illustrations it will be seen that my improved clip or fastening device is very simple, as well as secure and effective in use, and it will of course be understood that I do not limit myself to the details of construction and arrangement of parts employed herein in explanation of my invention.

35 40 By my construction I am enabled to employ ordinary cast-iron in the manufacture of the device and secure equally as good, if not better, results therefrom than are to be obtained from many former devices of the kind which 45 must be made of malleable iron in order to render them at all desirable or effective.

My device is simple and easily molded, and large numbers of the parts thereof can be put in the sand one day and made ready to 50 be delivered by the next, and thus are large orders enabled to be filled promptly without incurring any loss to the factory, as in the instances above mentioned with regard to malleable-iron clips or fastenings. Moreover, 55 the fastening-bolt employed by me is an ordinary machine-bolt including no special features of construction, and thus the purchase of the bolts is not confined to parties having special facilities for making them, 60 since said bolts are always carried in stock by almost all manufacturers and can be promptly furnished in any quantity on the placing of orders therefor.

65 By the use of my improved clip or fastening device a great advantage is had in the fact that less labor is required in constructing or putting up the harrow, there being no fitting

of castings to be performed and no clipping or grinding of burs, the device being all ready for use as it comes from the rattling mill. The clamping capacity of my improved clip is also very great, and the device forms a fastening for the harrow-tooth equally as secure as former malleable-iron fastenings for the same purpose.

Having thus fully described my invention, what I claim as new, and desire to secure by Letters Patent of the United States, is—

1. In combination with a supporting-bar substantially **U**-shaped in cross-section, a substantially hook-shaped clip having its shank constructed to abut against and partially enter between the edges of the bar and its hook confining a tooth between the same and said edges, and a fastening device located between the hook and shank for securing and holding the parts together.

2. In a fastening device for harrow-teeth, the combination with a supporting-bar substantially **U**-shaped in cross-section, of a detachable clip abutting against the edges of the bar and formed with a recess on its inner face, and a tooth clamped between said edges of the bar and the walls of said recess, substantially as described.

3. In a fastening for harrow-teeth, the combination with a supporting-bar substantially **U**-shaped in cross-section, of a detachable clip constructed to abut against the edges of the bar and having an angular recess in its inner face, and a tooth of angular cross-section clamped between said edges of the bar and the sides of said recess, substantially as described.

4. In a fastening device for harrow-teeth, the combination with a semitubular bar provided with a bolt-hole, of a clip having a similar hole between its ends and formed with a recess on its inner face, a bolt passing through said holes and secured by suitable means, and a tooth clamped between the edges of the bar and the walls of said recess with the shank of the hook abutting against the edges of the bar at one side of the fastening-bolt and the tooth at the other side thereof, substantially as described.

5. In a fastening device for harrow-teeth, the combination with a bar, of a detachable clip formed with a recess on its inner face, and a tooth clamped between the bar and the walls of said recess, said clip being also constructed to abut against the edges of the bar and formed on its outer face with strengthening-webs extending longitudinally thereof, substantially as described.

6. In a fastening device for harrow-teeth, the combination with a bar provided with a bolt-hole, of a clip having a similar hole and formed with an angular recess on its inner face, a bolt passing through said holes and secured by a nut, said clip being recessed on its outer face to receive the head of the bolt and prevent the latter from turning, and also formed with strengthening-webs, and a tooth

of angular cross-section clamped between the bar and the walls of said recess, substantially as described.

7. In a fastening device for harrow-teeth, the combination with a semitubular bar provided with a bolt-hole, of a hook-shaped clip having a similar hole and formed with a recess on its inner face, a bolt passing through said holes and suitably secured to hold the 5 shank of the clip against the edges of the bar with a portion between said edges, said clip being constructed on its outer face to receive the head of the bolt and prevent the latter from turning, and a tooth clamped between the bar and the walls of said recess, substantially as described.

8. In a fastening device for harrow-teeth, the combination with a semitubular bar, of a detachable clip partially received by said support and formed with a recess on its inner face, and a tooth clamped between the straight edges of the bar and the walls of said recess, substantially as described.

9. In a fastening device for harrow-teeth, the combination with a semitubular support, of a detachable clip partially received by said support for a portion of its length, and formed with an angular recess on its inner face, and a tooth of angular cross-section clamped between the straight edges of the support and the walls of said recess, substantially as described.

10. In a fastening device for harrow-teeth, the combination with a semitubular support, of a detachable clip partially received by said support for a portion of its length, and formed with a recess on its inner face, and a tooth clamped between the straight edges of the support and the walls of said recess, said 35 clip having shoulders abutting against said edges of the support, substantially as and for the purpose described.

11. In a fastening device for harrow-teeth, the combination with a semitubular support,

of a detachable clip partially received by said support and formed with a recess on its inner face, and a tooth clamped between the straight edges of the support and the walls of said recess, said clip being also formed with flanges abutting against said edges of the support, substantially as described.

12. In a fastening device for harrow-teeth, the combination with a semitubular support, of a detachable clip formed with flanges entering between the upper and lower sides of the support and having a recess on its inner face, and a tooth clamped between the straight edges of said support and the walls of the recess, said clip being formed on its upper and lower surfaces with flanges abutting against 50 said straight edges of the support, substantially as described.

13. In a fastening device for harrow-teeth, the combination with a semitubular support provided with a bolt-hole, of a clip formed 65 with a similar hole and having a recess, on its inner face, a bolt passing through said holes and secured by a nut, said clip also having flanges entering between the upper and lower sides of the support, and additional flanges 70 abutting against the straight edges of said support, and a tooth clamped between said straight edges and the walls of said recess, substantially as described.

14. A fastening device for harrow-teeth 75 consisting of a substantially hook-shaped clip having its shank constructed to partially enter between and abut against the edges of a two-edged supporting-bar, and a bolt between its hook and shank for drawing the latter 80 against said edges and confining a tooth between said hook and bar.

In testimony whereof I affix my signature in presence of two witnesses.
